US0D1009636S

(12) United States Design Patent (10) Patent No.: US D1,009,636 S
(45) Date of Patent: * Jan. 2, 2024

(54) BEVERAGE BOTTLE

(71) Applicant: Störtebeker Braumanufaktur GmbH,
Stralsund (DE)

(72) Inventors: Jürgen Nordmann, Rambin (DE);
Karsten Tribe, Rambin (DE)

(73) Assignee: Störtebeker Braumanufaktur GmbH,
Stralsund (DE)

() Term: 15 Years

(21) Appl. No.: 29/781,764

(22) Filed: Apr. 30, 2021

Related U.S. Application Data

(62) Division of application No. 35/507,615, filed on Mar. 20, 2019 (U.S. filing date under 35 U.S.C. 384), and having an international filing date of Mar. 20, 2019, now Pat. No. Des. 921,488.
